UNITED STATES PATENT OFFICE.

SIDNEY WEST, OF WASHINGTON, DISTRICT OF COLUMBIA.

ATHLETIC SOCK.

1,138,521.

Specification of Letters Patent.

Patented May 4, 1915.

Application filed August 26, 1912. Serial No. 717,173.

To all whom it may concern:

Be it known that I, SIDNEY WEST, a citizen of the United States, residing at Washington, in the District of Columbia, have invented new and useful Improvements in Athletic Socks, of which the following is a specification.

This invention relates to improvements in athletic socks.

- 10 In playing athletic games such as golf or tennis, wherein considerable running or other constant activity is required, the players prefer to use heavy woolen socks since these are easier on the feet than ordinary 15 socks of lighter material. These heavy woolen socks are held in place by garters in the ordinary manner, but the use of garters in playing these games is objectionable for two reasons, viz, first, it renders necessary 20 heavy woolen tops of considerable length which are highly uncomfortable; and second, because when the legs perspire the chafing of the garters is apt to develop blisters.
- 25 The object of the present invention is to avoid these objections and in furtherance of this object the invention proposes a sock having a short top which extends barely above the ankle and which has permanently 30 associated therewith a securing strap which takes the place of the usual garter and engages about the leg just above the ankle. In a preferred construction this securing strap is interwoven for a considerable part of its 35 length with the fabric of the top for the purpose of preventing the top from becoming stretched and of insuring its regular fit upon the leg when the securing strap is tightened. By this construction the use of 40 garters is rendered altogether unnecessary nor are any other elements employed which will chafe the leg; and it is practical to use a top of short length, which as stated, extends barely above the ankles and therefore 45 promotes the comfort of the user.

Embodiments of the invention are illustrated in the accompanying drawings, wherein:

- 50 Figure 1 is a perspective view showing one of the improved socks as in use. Fig. 2 is a sectional plan view showing more particularly the relation of the top of the sock and the securing strap. Fig. 3 is a sectional view showing that portion of the securing strap which is interwoven with the material of the sock. Fig. 4 is a detailed

vertical sectional view on the line 4—4 of Fig. 2.

Similar characters of reference designate corresponding parts throughout the several views.

The foot of the sock as A may be of any ordinary construction and the top B in the case of an athletic sock is of heavy ribbed woolen fabric. This top B as shown in Figs. 65 1 and 4 differs from the top of an ordinary sock in that it extends barely above the ankle and is not designed for engagement by a garter, but, instead, a securing strap is employed which has one end attached with 70 relative permanency to the top B somewhat near the upper edge of the latter and its other end, free. This strap encircles the small part of the leg immediately above the ankle and serves to prevent the top of the 75 sock from going below the ankle, and at the same time keeps the visible portion of the sock above the top of the shoe unwrinkled. Adjacent the end of strap is a buckle 2 of ordinary construction which is provided to 80 engage and secure the free end of said strap, and inwardly of said buckle there is a keeper 3 through which the free end of the strap passes. This keeper is preferably of fabric and may be secured to the sock in any 85 desired manner or it may be woven as a part thereof.

The strap 3 is preferably associated with the top B in the manner shown in Fig. 3; that is, by interweaving the strap for a considerable portion of its length with the top so that the top and the strap are virtually 90 integrally connected. This manner of associating the strap with the top is of advantage, first, in that it provides an intrinsically strong connection between the strap and the top, and, second, in that it prevents the top from being stretched for a portion 95 of its extent when the strap is engaged about the leg, as would be the case were the 100 strap simply secured by a line of stitching. Another advantage is that the top of the sock fits uniformly and regularly upon the leg being neither stretched nor wrinkled throughout its extent.

105 While the improvement is of particular advantage in connection with athletic socks composed of heavy woolen fabric, it is within the purview of the invention to apply the improvement to socks of lighter material and not especially designed for athletic purposes, in case such application 110

should for any reason be found necessary or desirable.

Having fully described my invention, I claim:

- 5 As a new and complete article of manufacture, a sock, consisting of a lower portion adapted to completely incase the foot of the wearer, an upper portion integral with said lower portion and incasing the ankle of the
- 10 wearer, the upper portion being of a length to come barely above the ankle, a strap permanently attached to said upper portion wholly within the area thereof and adapted

to encircle that portion to bind the same about the ankle of the wearer, the strap being interwoven for a portion of its length with the material of said upper portion, and means carried by said upper portion to secure the ends of the strap.

In testimony whereof I have hereunto set 20 my hand in presence of two subscribing witnesses.

SIDNEY WEST.
